DESIGN FOR A WALLET

Charles Panzer, New York, N. Y.

Application December 15, 1945, Serial No. 124,781

Term of patent 3½ years

(Cl. D87—3)

To all whom it may concern:

Be it known that I, Charles Panzer, a citizen of the United States, residing in the Borough of Manhattan, county and State of New York, have invented a new, original, and ornamental Design for Wallet, of which the following is a specification, reference being had to the accompanying drawing, forming a part thereof.

I claim:

The ornamental design for a wallet, as shown.

CHARLES PANZER.
